CLAIM

The ornamental design for a “sanitary storm and catch basin trap,” as shown and described.

DESCRIPTION

FIG. 1 is an oblique view of a sanitary storm and catch basin trap having a fish mouth attachment;

FIG. 2 is an oblique view thereof showing the fish mouth portion detached from the trap portion;

FIG. 3 is a front view showing the trap portion and the fish mouth portion;

FIG. 4 is a right side view showing the fish mouth portion detached from the trap portion;

FIG. 5 is a left side view showing the fish mouth portion detached from the trap portion;

FIG. 6 is a top view showing the fish mouth portion detached from the trap portion;

FIG. 7 is a rear view showing the fish mouth portion detached from the trap portion; and,

FIG. 8 is a bottom view showing the fish mouth portion detached from the trap portion.
